PAPER CUTTER

David O. Chase, Camillus, Philip H. Stevens, Syracuse, and Alan W. Brownlie, Skaneateles, N.Y., and John A. Malm, Rocky River, Ohio, assignors to The Chandler & Price Company, Cleveland, Ohio, a corporation of Ohio

Original design application Nov. 3, 1966, Ser. No. 4,542, now Patent No. 210,691, dated Apr. 2, 1968. Divided and this application Oct. 11, 1967, Ser. No. 10,592

Term of patent 14 years

(Cl. D55—1)

FIG. 1 is a top plan view of a paper cutter embodying our new design;

FIG. 2 is a front elevation thereof;

FIG. 3 is a side elevation thereof as seen from the right in FIGS. 1 and 2;

FIG. 4 is an opposite side elevation thereof as seen from the left in FIGS. 1 and 2; and

FIG. 5 is a rear elevation thereof.

This is a division of design application, Ser. No. 4,542, filed Nov. 3, 1966, entitled Paper Cutter, now Patent No. D. 210,691.

We claim:

The ornamental design for a paper cutter, as shown and described.
